UNITED STATES PATENT OFFICE

ROBERT JEWETT PABODIE, OF MAYWOOD, ILLINOIS, ASSIGNOR TO THE GRISCOM-RUSSELL COMPANY, OF NEW YORK, N. Y., A CORPORATION OF DELAWARE

HEAT EXCHANGER

Application filed September 4, 1926. Serial No. 133,525.

This invention relates to heat-exchanging in general and resides in certain improvements in multiple-section cooling apparatus.

In oil refinery work and in other work in which a fluid other than a non-corrosive liquid such as water is the medium to be cooled or heated by surface heat exchanging, due provision must be made for the corrosive and clogging effects of the medium. It is also imperative that the utmost possible efficiency be obtained in transferring the heat content of this medium, as,—for example, in gasoline producer plant operation,—the operativeness of the plant may depend entirely upon the completeness with which the heat content of the medium is interchanged in certain stages of the flow of the medium. The mechanical construction of the heat exchanger is an important item and applies particularly to the attaining of the maximum thermal efficiency in the particular form of construction employed, per unit of length, and also the flexibility of the assembly as a whole as regards varying its constituents to meet changing operating conditions. The floor or wall space occupied by the multiple-section assembly is, of course, in some cases controlling, but probably the most important consideration of all is the way in which the parts are designed and put together and the degree of mechanical efficiency in operation of the assembly, such as the fluid-tightness of the joints, ease of cleaning, and control of expansion strains and the like.

It is contemplated by the present invention to provide a multiple-section heat exchanger which shall be of general usefulness and adapted for employment for heat exchanging between all kinds of fluids, whether they be corrosive or non-corrosive in action, or sluggish, or rapid in flow.

It is another primary object of the invention to provide a heat exchanger in which an increased rate and efficiency of heat exchange

shall result from directed flow of the media therein.

It is also an object of the present invention to provide a heat exchanging apparatus or cooling machine, in which there shall be little or no tendency to cause deposition of clogging matter within its enclosures, walls, or sides, and further, shall be susceptible of easy and rapid cleaning in case it should be used in work in which such deposition is unavoidable, as in handling fluids carrying an unusual amount of sediment.

Another object of the present invention is to furnish an apparatus of this class which shall have sections capable of manipulation and easy adjustment in such a manner as to prolong the life of the heat exchanger beyond that expected of ordinary heat exchangers.

A particular object of the present invention is to reduce the number of joints required in a sectional heat exchanger, and additionally, to make and maintain these joints fluid-tight, not only on the outside enclosures of the heat exchanger, but on the inside enclosures as well.

A further particular object of the present invention is to provide a heat exchanger, of this type which shall be capable of trapping off any liquids which may be fractionated therein, in order to increase the efficiency of the heat exchanger.

A still further particular object of the present invention is to accommodate all expansion strains which may tend to occur in the heat exchanger, and in such a manner that no gaping or opening at the joints can occur.

The invention will be further described in connection with the accompanying drawings forming a part of the specification and which disclose only those of the various successful embodiments of the present invention, which have been chosen to be herein disclosed. It is to be understood that these drawings and the subsequent description thereof are given only for the purpose of specifically disclos-

ing a few typical forms of the present invention, and the invention does not lie solely therein, nor is it confined thereto.

In these drawings,

5 Figure 1 is an elevational view of one embodiment of the present invention;

10 Figure 2 is a longitudinal, sectional view of one of the combination return-bend and double-pipe flow elements, shown in Figure 1, with portions of the element broken away for convenience;

15 Figure 3 is a view along line 3—3 of Figure 2, sighting in the direction of the arrows;

20 Figure 4 is a vertical, longitudinal, sectional view of another embodiment of the present invention;

25 Figure 5 is a sectional view of one of the elements of Fig. 4;

30 Figure 6 is a view along line 6—6 of Figure 5;

35 Figure 7 is a sectional view of one of the joints of Figure 4;

40 Figure 8 is a vertical, longitudinal, sectional view of an extension flange designed to connect two flow-sections in series;

45 Figure 9 is a detail view of two double-pipe flow sections connected in series by means of the extension flange shown in Figure 8;

50 Figure 10 is a fragmentary front elevation, partly in section, of still another embodiment of the present invention;

55 Figure 11 is a sectional view along line 11—11 of Figure 10, sighting in the direction of the arrows;

60 Figure 12 is a fragmentary front elevation, partly in section, of still another advantageous embodiment of the present invention;

65 Figure 13 is a sectional view along line 13—13 of Figure 12, sighting in the direction of the arrows;

70 Figure 14 is a fragmentary front elevation, partly in section, of a further embodiment of the present invention, and

75 Figure 15 is a sectional view along line 15—15 of Figure 14, sighting in the direction of the arrows.

80 Referring now to the drawings more in detail by numerals, an advantageous embodiment of the invention is shown in Figures 1 and 2 as comprising straight, concentric pipes 1, and concentric return-bends 6, to which are connected two of the sections 1 to form a U-flow section. The sections are preferably of cast iron, and are U-shaped in order to effect the greatest distance of travel of the contained fluids in the smallest possible floor or wall space, and for other purposes to be hereinafter explained. The elements 1 can be connected together as shown, by the return-bends 6, forming complete, directed-flow and counter-flow passageways for the fluid to be cooled and the cooling fluid, respectively.

85 The general structure of the return-bends 6 is similar to that of the elements 1 inso-
90 much as the inner and outer bend elements are made integral with each other by the use of a plurality of lugs 5,—here shown as four in number,—cast between these bend elements at each end of the return-bend, the connecting projections or bolting ears 7 being cast on the return-bend in the positions shown in Figure 3. The true positions of these lugs 75 is not shown in Figure 2, the positions shown in Figure 3 being more accurate. The center ones of the ears 7 may be cast together, as shown in Figure 3, in order to prevent the return-bend from springing out of the proper shape, and the two inside or center ears 7 of the connected flow-sections 1 may likewise be cast integral but it is preferred to leave them unconnected and in stub form, in order to permit the accomplishment of the object 80 of prolonging the life of the flow sections, by adjusting and manipulating them in a manner to be described later.

90 Near each end of each element 1, are cast a plurality of connectors or lugs 4, which may be similar to the lugs 5 in the return bends, and—here shown as four in number—in which connect solidly an inner concentric pipe 3 to an outer concentric pipe 2. These connecting bridging or spacing lugs 4 are cast narrow in the direction of flow of the medium by which they are traversed, in order to offer as little head resistance as possible to the fluid-flow. These lugs 4 make integral 95 the two concentric pipes 2 and 3 so that they can all be cast in one mold. These bridging lugs are further contemplated by the present invention as being so arranged in the interior of the pipe-section as to straddle the vertical center-line of the section, as shown, so as to form an unobstructed, non-clogging flow path 100 therein.

105 On the outside of the exchanger, at each end of an element 1, there are formed a plurality of projections, bolting-lugs or ears 7, here shown as four in number, and provided with suitable openings or bolt holes for receiving bolts or other suitable fastening means. These projections or ears 7 are formed 110 on the outside of the outermost of the concentric pipes, always directly opposite the connecting or spacing lugs 4, and on the same perpendicular axis therewith, in order to concentrate the pull of the connecting bolts 115 to this point and thereby to make and maintain an absolutely fluid-tight joint.

120 These projections or ears 7 are spaced 90° apart on the periphery of the outer walls 2. The reason for this arrangement of parts is 125 that, when for example, a gaseous fluid is being passed through the exchanger, the condensate will invariably settle to the bottom of each section and run along in a comparatively narrow and restricted path. Even 130

cast-iron walls such as those of the exchanger of the present invention would eventually show wear or channeling from this action, and it is hence contemplated by this invention to increase the span of life of heat exchangers as much as fourfold by spacing the lugs 7 at 90° to each other, so that whenever it is thought that channeling has taken place, it will be possible to not only merely lift out the entire assembly and turn it upside down, thus exposing a new, smooth surface to the action of the condensate, but also to disassemble the various pipe elements 1 and return bends 6 and turn the sections through a vertical angle of 90°, to thus bring into contact with the eroding liquid, a new, unimpaired surface. Inasmuch as this rotation can be performed four times in 360°, it is evident that the life of each section is quadrupled by this construction and arrangement of parts.

The spacing projections or lugs 4 connecting together the inner and outer pipes 2 and 3 straddle the vertical center line of the cross-sectional area of the passage ways 23, as will be evident from Figure 3, thereby leaving unrestricted the path naturally followed by condensate which may form within the exchanger. This feature efficiently prevents any clogging of the outer enclosure or gas-side.

At the top and at the bottom of the assembly, there are provided inlet and outlet connections or fittings 26. These fittings are connected or bolted to the element 1 in a manner similar to that in which the elements are connected together, as will be seen from Figure 1. According to one method of employing the heat exchanger of the present invention, the medium to be cooled, or the hot medium, of any composition or in any fluid state, enters through the connection or inlet 18, passing in directed flow through the outer annular space or gas-side 23 of the exchanger, and discharging through the outlet 16; and the cooling medium, or waste fluid, is admitted through the connection or inlet 15, passing in directed counter-flow through the water-side 22' of the exchanger and discharging through the outlet 14.

At the return bend end of each bottom member of the assembled members, and optionally also at the bend-end of higher sections, may be provided enlargements or liquid pockets 9, for the purpose of trapping liquids condensed at fractional temperatures where the fluid or gas to be condensed flows through in the outer annular space 23. These fractionated liquids may then be drawn off through openings or plug holes 21'. However, the heat exchanger of the present invention is capable of being used for work in which these pockets 9 may be superfluous or even deleterious, and therefore it is to be

understood that this enlargement or pocket is not imperative in the functioning of the apparatus of the present invention.

As shown in Figure 2, the elements or double-concentric pipes 1 are connected to the return bends by suitable bolts passing through the projections or ears 7, and the fluid tight integrity of the joints 25 is preserved by the means hereinbefore referred to, in conjunction with the inner packing-rings or ring molded gaskets 19 and outer gaskets 19', which are composed of suitable material. It is a part of the present invention to make the outer gaskets 19' slightly thicker than the inner gaskets 19 in order to compensate for the pull of the bolts connecting the joints together, which pull will always tend to be slightly heavier on the outside than on the inside. These features thus maintain absolutely fluid-tight joints throughout the apparatus. The gaskets are centered by the centering rings 11 and locked by gaskets holding-rings 12, as best seen in Figure 2.

If desired, adjustability for long life may be sacrificed to high rate of flow, and the joints 25 may have their faces 10° pitched to a predetermined degree, as shown best in the alternative forms in Fig. 5 or Fig. 2, in order that each flow section 1 may have a downward slope to facilitate the flow of the fluids therein. It is to be understood, however, that the invention does not contemplate the necessity of making every embodiment thereof in this manner, as this structure is not mandatory and the heat exchanger operates satisfactorily without being so made.

In Figure 3 are shown the faces of the joints 25, looking in the direction of a bend 6, and it is seen that the connecting lugs 4 and 5 straddle the vertical center line of the section and thus leave a free and unrestricted passage for the flow of the condensate and hence there is no tendency whatsoever for the flow in the exchanger to become clogged.

Each of the return-bends 6 may be provided on its lower surface with a hollow chair 9 which will thus serve both as a spacing member and as a trap for fractional condensates forming in the outer side 23. On the upper surface of each return-bend 6 may be provided a solid chair 9', in order to complete the spacing means between the U-bends of the assembled sections.

By making the lugs 7, on the inside of the turn of the return-bends 6, integral across the bend, as shown in Fig. 1, and better in 7⁴ of Fig. 3, the entire assembly can be lifted up as a unit and turned upside down, for the purpose hereinbefore described.

In Figures 8 and 9 is shown an extension flange 17. Due to mechanical difficulties, the length in which the flow-sections 1 can conveniently be made is limited. There arise, however, in practical operation, conditions where it is desirable, in order to attain

to the correct ratio of length of travel of the fluids to ideal heat transfer for the particular conditions and fluids in question, to have long assemblies of the straight path pipes, but 5 only one or two sections high. By means of this element of the invention, that is, the extension flange 17, this desideratum can be accomplished. This extension flange is a double-faced flange with both sides or faces similar in construction to the return-bend shown in Figures 2 and 3. The inner pipe-section 3' is made integral with the outer pipe 2', by lugs 4', and suitable connections or bolts can be placed in the bolt holes 18 provided in the 15 ears 7'. The locking rings 12' and centering rings 11' function as shown in Figure 9 to properly hold in place the two pipe sections to be connected in series. It is evident that by the use of this flange as many sections as 20 are deemed necessary can be placed together in series, or in combination with the return-bends 6, according to the desired ratio of heat transfer to length of travel of the fluids.

In Figures 4, 5, 6 and 7 is shown an embodiment of the present invention differing from the embodiment shown in Figures 1 to 3 inclusive in that it comprises elements 1' formed integral with the elbows or return-bends of Figures 1 to 3 inclusive. The advantages of 25 this modification are that it combines a lowered cost of manufacture with an equal mechanical and thermal efficiency.

In Figures 10 and 11 is shown a modification of the embodiment shown in Figures 1 to 3 inclusive, which differs from that embodiment in several important structural features, notably in the advantageous location and shape of the spacing lugs 5, whereby the 35 number of lugs required is decreased; the different design of the bolting lugs 7'; and the elimination of the chairs 9. This modification can, as well as the modification shown in Figure 5, also be provided with pockets or traps 9.

In Figures 12 and 13 is shown another modification of the embodiment shown in Figures 1 to 3 which differs from those embodiments in comprising several structural variations therefrom, notably in that, though 45 there are separate return bends and separate inlet-outlet pieces, successive straight pipe elements 1 are connected vertically by a web, such as 24. Also, the inner pipe in the straight elements, is separate from the outer 50 and rests on it by means of lugs 4, by which lugs it can be brought into four different positions with four different sides of the pipe occupying the bottom position.

In Figures 14 and 15 is shown still another 60 modification of the embodiment shown in Figures 1 to 7, which differs therefrom in that the lugs 4 are modified into combined bolting and spacing lugs 4'; in that the inlet and outlet connections are simplified, and in 65 that many other structural simplifications are

embodied which are evident from the figures. The inner and outer concentric pipes are not cast integral, but instead the smaller inner pipe 3 rests on the inner surface of the larger pipe 2 by means of the lugs 4', which also serve to join the various sections of the pipe 3.

By means of the heat exchanger of the present invention, the heat content of many different kinds of fluids that have heretofore been found difficult to handle satisfactorily 70 because of their extreme viscosity or semi-fluidity, and their corrosive or reactive nature as well as their tendency to condense and deposit solids in large quantities within the apparatus, can be transferred with a thermal efficiency approaching closely to the maximum and with a rate and consequent capacity, beyond that ordinarily obtained in tortuous flow, surface contact, heat exchangers.

In practice, the heat exchanger of the present invention occupies a floor or wall space which is small in proportion to the volume of the fluids which can be operated upon per unit of time. The ever present liability of leaky and heat losing joints is decreased by 75 eliminating most of the joints. The same improved structure which assures the proper length of travel of the fluids for satisfactory heat transfer for the fluids in question also permits of easy access to the cleaning purposes when working with materials holding 80 easily precipitated solids in a "sol" condition therein; and incidentally, reduces clogging of the improved flow-paths therein. As a matter of a purely economic nature, the reversible flow-sections constitute the heat exchanger an apparatus which has substantially 85 four times the durability of that of the usual type of tortuous flow heat exchangers. 90

I claim:

1. A heat exchanger, comprising a plurality of flow-sections, said sections being formed into an upper arm and a lower arm connected by a return bend in such a manner 100 that the flow through each section at its outlet end is substantially opposite in direction to that at its inlet end, each of said sections having an inner conduit and an outer enclosure therefor, said inner conduit and said outer enclosure being integrally connected near each end of each section to form an annular space between said inner conduit and said outer enclosure; an upper inlet and outlet connection; a lower inlet and outlet connection; and on the outside of each section and on each return bend, at the ends thereof, means for connecting together said sections and bends in a continuous vertical arrangement.

2. In a heat exchanger of the class described, a plurality of U-flow heat-transferring sections, comprising a plurality of concentric pipes integrally connected at each end in the interior thereof, by projections 110

therebetween; and having on the outside of one end of said sections on the same perpendicular axes as said connections, means for connecting said sections to return bends.

5 3. A heat exchanger comprising a plurality of integrally-concentric pipes and return bends, connected together at their ends on their interiors by spacing lugs, said bends having at said ends, inner centering lips and outer locking lips, said lips forming recesses to receive outer and inner ring gaskets; and around the periphery of the outermost of the concentric pipes and bends, at the ends thereof and on the same perpendicular axes as the 10 said lugs, a plurality of equidistant projections so placed as to connect together said pipes and bends, and to concentrate the connecting-pull along these axes.

4. A heat exchanger of the class described, comprising a flow-section having integrally 20 concentric pipes, a return-bend having integrally concentric pipes, a double-pipe inlet connection, a double-pipe outlet connection and a chamber formed in the wall of the 25 outermost of the concentric pipes, on the lower side of one of said bends.

5. A heat exchanger, comprising a plurality of elements, each of said elements including two concentric pipes, said elements being 30 arranged one above the other in a vertical plane and being connected in series by return bends to form zigzag passages, each of said elements being separated from and supported above the next lower element by a hollow 35 chamber on the lower side of the upper of the adjacent returns bends, and a solid chair on the upper side of the lower of the adjacent return bends.

6. In a heat exchanger of the class described, a plurality of heat-transferring elements, comprising a plurality of concentric pipes integrally connected at each end in the interior thereof, by projections therebetween; and means on the outside of said sections and 40 on the same radial lines as said connections, for connecting said elements to return bends.

7. In a concentric pipe element, return bend heat-exchanger, means whereby a channel worn in the bottoms of the pipes may be replaced by a fresh, unchanneled surface, comprising a plurality of bolting lugs on the outer periphery of the ends of the separate pipe elements and spaced equidistantly there-around, and an equal number of bolting lugs 50 equally spaced around the ends of the arms of the return bends against which said pipes abut.

8. In a concentric pipe element, return bend heat-exchanger, joints between said pipe elements and said bends, and a structure for preventing said joints from opening up under operating stresses, comprising a plurality of bridging lugs connecting said concentric pipes to each other at each end thereof and 55 connecting the concentric pipes in the return

bends at each end of said return bends, and an equal number of bolting lugs for holding said pipe sections and bends together, said bolting lugs being disposed equidistantly on the ends of the outer periphery of the outer 70 concentric pipe on the line-prolongation of the axes of said bridging lugs.

9. In a concentric pipe-element heat exchanger, an inner conduit, an outer conduit 75 encasing it, and bridging lugs at each end of each element for connecting said conduits integrally, said bridging lugs being disposed on both sides of the vertical center line of each of said pipe-elements so as to straddle said center-line and thereby form an unobstructed central flow-passageway in the pipe 80 element.

10. A heat-exchanger of the type described, having a plurality of pipe elements connected at their ends to form flow-channels by return 85 bends, each element comprising a smaller pipe and a larger pipe, the smaller pipe being connected concentrically with the larger pipe by integral lugs, other lugs extending out beyond the outer side of said larger pipe and in line 90 with the first-mentioned lugs for connecting the elements to the bends, said outer lugs being so spaced on the exterior of the outer pipe as to transmit the connecting strains to the inner pipe, whereby no unbalanced forces come on 95 said connection.

11. A heat exchanger of the type described, having a plurality of double-pipe elements connected at their ends by double pipe return 100 bends, each element including a smaller pipe and a larger pipe, the smaller pipe being formed concentrically integral with the larger pipe by lugs therebetween, said lugs being located in pairs to one side of the top and bottom ends of the vertical center-line of the element and other lugs on the outside of the larger pipe and in line with the first-mentioned lugs forming means for connecting said sections to said bends, whereby no longitudinal unbalanced forces exist at said connection. 110

12. A heat exchanger of the type described, having a plurality of double pipe elements connected at their ends by double pipe return bends, each element including a smaller pipe and a larger pipe, the smaller pipe being formed concentrically integral with the larger pipe by lugs therebetween, said lugs being located in pairs to one side of the top and bottom ends of the vertical center-line 115 of the section, and other lugs on the outside of the larger pipe and in line with the first mentioned lugs forming means for connecting said sections to said bends, said return bends comprising pipes held in concentric relation by lugs in their interiors at each end and other lugs on their exteriors to connect the bends with the elements. 120

13. In a heat exchanger comprising double 125 concentric pipe-elements and double concen-

tric return bends connecting said pipe elements, a joint between the bends and the elements comprising lips on the ends of the inner pipe of the return bend, tongues on the inner pipe of the pipe elements, lugs connecting the concentric pipes of the pipe elements at the ends of the pipe elements, lugs on the outside of the pipe elements forming connecting ears, and complementary similarly placed lugs on the ends of the return bends, for connecting the pipe elements to the return bends at said joint.

In testimony whereof I affix my signature.
ROBERT JEWETT PABODIE.
